UNITED STATES PATENT OFFICE

DAVID C. CHURCHILL, OF BEREAL, KENTUCKY

DESIGN FOR A SIGN

Application filed October 25, 1930. Serial No. 37,374. Term of patent 7 years.

To all whom it may concern:

Be it known that I, DAVID C. CHURCHILL, a citizen of the United States, residing at Berea, in the county of Madison and State of Kentucky, have invented a new, original, and ornamental Design for Signs, of which the following is a specification, reference being had to the accompanying drawings, forming a part thereof, in which—

Fig. 1 is a plan view, and Fig. 2 is a perspective view of a sign showing my new design.

I claim:

The ornamental design for a sign as shown. In testimony whereof, I hereunto affix my signature this 11 day of Oct., 1930.

D. C. CHURCHILL.
